UNITED STATES PATENT OFFICE.

CHARLES W. DIPPERT, OF BUFFALO, NEW YORK.

RADIATOR.

Application filed April 1, 1920. Serial No. 370,411.

To all whom it may concern:

Be it known that I, CHARLES W. DIPPERT, a citizen of the United States, residing at Buffalo, in the county of Erie and State of New York, have invented a new and useful Improvement in Radiators, of which the following is a specification.

This invention relates to radiators of the kind used in connection with motor vehicles or the like. The objects of this invention are to provide improved water tubes for radiators of this kind which are made in two parts and which are so constructed as to facilitate the assembling and construction of the tubes; also to so construct the water tubes as to facilitate the construction of the radiator; also to provide a radiator of this kind with radiating fins or webs of improved construction; also to improve the construction of radiators of this kind in other respects hereinafter specified.

In the accompanying drawings,

Fig. 1 is a front elevation of a radiator embodying the invention.

Fig. 2 is a fragmentary transverse sectional elevation thereof showing on an enlarged scale, the core of the radiator.

Fig. 3 is a perspective view of an end of one of the water tubes of the radiator core.

Figs. 4 and 5 are perspective views of the ends of the two parts comprising the water tube.

Fig. 6 is a perspective view of a radiating web or fin of the radiator.

Fig. 7 is a horizontal section on line 7—7 Fig. 3, showing on a still larger scale one of the water tubes.

In the radiator shown in Fig. 1, A represents the upper reservoir or manifold of a radiator and B represents the lower reservoir or manifold, the two reservoirs being connected by a plurality of tubes C through which the water flows from one reservoir to another, the water being cooled while passing through the tubes C.

The tubes C as shown in Figs. 3, 4, and 5 are made in two main parts or sections. One of these parts or sections D is provided at its front and rear portions with turned over or channelled parts d preferably formed integral with the part D by turning over the edge portions of the section D. The other portion E of the radiator is in the form of a substantially flat strip of metal and is adapted to be held in operative relation to

the part D by means of the channelled or turned over edge portions d. The contacting edges of the two parts of the tube are dipped in solder or analogous medium, which forms a water tight joint between the two parts of the tube. A tube of this construction has the advantage that it can be very easily assembled by sliding the part E lengthwise along the channels d. This structure has the further advantage of having three thicknesses of metal at the front and rear edges of the water tube which greatly strengthens these parts of the tube and thereby forms a durable and strong water tube. 60 Either of the two parts or sections of the water tubes is preferably provided with spacing portions, which in the construction shown, are provided on the section D of the water tube and are formed integrally therewith. For this purpose the part D is provided with projecting portions d' which when the tube is assembled extend into the water passages and space the two side walls or parts of the tube from each other. These 65 spacing projections are preferably somewhat elongated but do not extend throughout the full length of the water tubes, and thereby permit the water in a tube to circulate to all parts of the tube. 70

In order to assemble the tubes to form the core of a radiator, each section of the tube is provided at opposite ends with projecting lips or flanges F, F' which extend substantially at right angles to the body portions of 75 the tubes. When the core of the radiator is assembled, these projecting flanges or lips overlap as shown in Fig. 2, and are secured together by means of solder or analogous material, the lips or projections of the ends of 80 the water tube forming a simple lap joint which may constitute one of the walls of each of the manifolds or reservoirs A and B. This lap joint construction greatly facilitates the assembling of radiator cores 85 since no interlocking of the ends of the water tubes is necessary. This construction also requires less material and consequently produces a lighter core than constructions in which interlocking joints are used and 90 greatly reduces the cost of the radiator since no interfitting of parts is necessary. 95

The radiation of heat from the water tubes is assisted by means of radiating webs or fins G, which in the construction shown 100 are made of thin strips of metal bent to form substantially flat portions g adapted to bear

against the flat faces of the water tubes, and curved or rounded portions g' connecting the flat portions g and extending into the air spaces between adjacent water tubes. 5 In the construction shown, two of these radiating fins are provided in each air space between adjacent water tubes and these fins are oppositely arranged so that the outer surfaces of the curved or rounded portions g' 10 are in contact and thus assist in spacing the parts of the radiator core. In radiators of this kind as heretofore constructed, these fins form a plurality of air passages extending from the front to the rear sides of 15 the radiator, which passages are practically imperforate or closed so that air can not pass from one passage to another. I have found that better cooling of the water can be effected by providing means for permitting 20 air to flow from one passage to another, as well as through the passages from end to end. In order to accomplish this result, the fins G are provided at the outer faces of 25 the curved portions g' with perforations H extending lengthwise of the curved portions g' . When the fins are in place in the radiator core the perforations H in the two fins are substantially in registration so that the 30 air is free to circulate between the various air passages of the radiator core. Sufficient metal is left in the outer faces of the curved portions g' of the fins so that these portions of the fins will be in contact to properly space the fins in the air spaces. 35 In the forming of the fins, I have found that greatly improved results can be obtained by forming the flat portions g without any perforations so as to not impair the strength or resistance to bending of these 40 parts of the fins. By using the construction shown in the drawings in which the flat portions are imperforate, these portions will lie flat against water tubes of the radiator and will operate with the greatest efficiency in 45 conducting heat from the water tubes to the radiating fins. When the flat portions g are provided with perforations the metal along the line of the perforations is weakened so that these parts of the metal tend to bend, 50 with the result that the perforated portions are no longer flat and contact with the water tubes only along the edges of the contacting faces, instead of contacting along their entire faces. Thus by making the flat 55 portions imperforate the flat portions of the fins contact with the water tubes in such a manner as to efficiently conduct heat from the tubes, and these flat portions by lying closely to the flat tubes, draw the solder by 60 capillary attraction from the faces of the radiator to the interior thereof, so that by dipping only the front and rear faces of the 65 radiator in solder, the solder will run between the adjacent faces of the tubes and fins and form a good heat conducting con-

nection, without coating the other intermediate portions of the tubes and fins with solder.

In assembling the radiator, the two sections of the tubes are first assembled and the fins are then placed between adjacent tubes. The flanges or lips F F' form stops or guides which position the fins correctly relatively to each other and to the water tubes. The water tubes can be easily placed 75 into proper relation to each other since the flanges or lips do not require interlocking or special fitting.

I claim as my invention:—

1. A water tube for a radiator including two sections forming the sides of the tube, one of said sections having its edges bent over and spaced from the body portion of said section to form channelled edge portions, the edges of said other section engaging said spaced edge portions, means between the edges of said sections for holding the sections in spaced arrangement, whereby one section may be slid lengthwise of 85 said other section and held in operative relation thereto, a water tight connection being formed between the edges of said sections by means of solder or the like.

2. A flat water tube for radiators including two sections forming the sides of the 95 tube, one of said sections having its opposite edges bent over and spaced from the body portions to form channel shaped portions adapted to receive the edges of the other section, the body portion of which is 100 substantially flat, and spacing projections formed on one of said sections between the edges thereof for forming a water circulating space between said sections, whereby said tube may be assembled by sliding said 105 sections lengthwise into their operative positions, said sections being secured together by dipping the edges thereof in solder or the like.

3. A radiator comprising water tubes each 110 including two sections forming the sides of the tube, one of said sections being provided with overturned edge portions which are spaced from the body portion of the section and form guides for engaging the relatively flat edge portions of the other section to loosely hold the two sections in operative relation to each other, means arranged between the edges of said sections 115 for holding said sections in spaced relation to each other, and spacing fins arranged between adjacent tubes and having flat faces lying substantially in contact with the tubes, a water tight connection being formed between the edges of said tubes by solder or 120 the like which also secures said flat portions of said fins to said tubes.

4. A radiator having a plurality of water tubes each including two sections forming the sides of the tube, the opposite edges of 130

- said sections being adapted to interlock to hold said sections in place and arranged at the front and rear faces of the radiator, one of said sections being provided with projecting parts intermediate of the edges thereof adjusted to engage the other section for spacing said sections with regard to each other and for holding said sections in interlocking engagement, and spacing fins arranged between adjacent tubes, a water tight connection being formed between the edges of said sections by solder or the like, which also secures said fins to said tubes at the front and rear faces of the radiator.
- 5 10 15 5. A radiator having a plurality of water tubes each including two sections forming the sides of the tube, the edges of one of said sections being bent back to engage the edges of the other section, said engaging
- edges being arranged at the front and rear 20 faces of the radiator, one of said sections having integral inwardly extending portions between the edges thereof engaging the other section for holding said edges in engagement, and spacing fins arranged between each pair of tubes, the opposite faces of the radiator when assembled being dipped in solder, forming a connection between said fins and between the fins and said tubes, and soldering said interlocked edges of said 30 tubes.

Witness my hand this 29th day of March, 1920.
